ATTYS.

UNITED STATES PATENT OFFICE.

ENGWALD JHON SORTLAND, OF NEUTRAL VALLEY, ALBERTA, CANADA.

CATTLE-GUARD.

1,217,651.

Specification of Letters Patent. Patented Feb. 27, 1917.

Application filed November 13, 1916. Serial No. 131,167.

To all whom it may concern:

Be it known that I, ENGWALD J. SORTLAND, a subject of the King of Great Britain, and resident of Neutral Valley, in the Province of Alberta, Dominion of Canada, have invented certain new and useful Improvements in Cattle-Guards, of which the following is the specification.

This invention relates to cattle guards particularly adapted to be utilized on railway crossings and the like, and the object of the invention is to provide for the automatic operation of the cattle guard thereby preventing animals from straying on the railway track. Further objects are to render the guard compact in construction and to adapt the several parts to better perform the functions required of them.

With the above and other objects in view the invention consists essentially of the improved construction particularly described and set forth in the following specification and accompanying drawings forming part of the same.

25 In the drawings,

Figure 1 is a perspective view of a railway crossing embodying the present invention.

Fig. 2 is a transverse section of the improved cattle guard.

Like characters of reference refer to like parts in the several figures.

Referring to the drawings, A represents the cattle guard consisting of a casing 10 designed to be partially embedded in the ballasting and located below the rails of the track B and extending transversely under the same, the said casing carrying a shaft 11 rotatably mounted therein.

40 This shaft is rigidly attached to the lower end of a plurality of barrier members C which are adapted to lie in a normally horizontal plane and are located intermediate of the rails of the track and on opposite sides of the track and designed to be rotated in a vertical plane in a manner to be made clear hereafter.

The casing 10 is provided with a top 12 capable of vertical movement and carrying on its underface a plurality of brackets 13 provided with racks 14 meshing with the pinions 15 rigidly mounted on the shaft 11 thereby facilitating in transmitting rotary motion to the said shaft when the said top 55 is depressed.

The top 12 is held normally spaced from

the casing 10 by the spiral spring 16 located between the bottom of the said casing and the bracket 17 mounted on the cover plates 18 carried by the top. These cover plates 60 are designed to bridge the opening between the top 12 and the body of the casing 10 thereby preventing the track ballasting from entering the casing and impeding the action of the mechanism housed thereon.

65 The assembly of the guard will be readily understood from the foregoing description.

When the cattle guard is in use the barrier members C occupy a normally horizontal position and on an animal straying on the railway track and coming into contact with the top 12 of the casing 10 rotary motion is transmitted to the shaft 11 which in turn rotates the barrier members C through a substantial right angle and bars the passage 75 of the animals.

Although under ordinary circumstances the barrier members C would return to their normally horizontal position under gravity, it will be understood that the upward movement of the cover 12 is accelerated by the spiral spring 16 so that there is no liability of the barrier members being retained in a vertical position and that under all circumstances they are returned to their normally 80 horizontal position, thereby leaving the track open to traffic.

85 From the above description it will be seen that I have invented a cattle guard which can be advantageously employed on railways and the like and in which the barrier member is automatically operated to prevent animals straying on the railway track.

90 As many changes could be made in the above construction and many apparently 95 widely different embodiments of my invention, within the scope of the claim, constructed without departing from the spirit or scope thereof, it is intended that all matter contained in the accompanying specification and drawings shall be interpreted as 100 illustrative and not in a limiting sense.

105 What I claim as my invention is:

A cattle guard of the class described comprising a casing having a diagonally extending lateral entrance thereto, a transversely extending shaft operatively mounted in the casing, a pinion wheel on the shaft, a plurality of barrier members having offset ends passing through said lateral entrance 110 and operatively connected to the shaft and designed to lie in a normally horizontal

plane, a cover normally elevated from said casing, cover plates carried by the cover designed to bridge the space between the said cover and casing when the cover is elevated, 5 vertical racks operatively supported by the cover meshing with the pinion wheels, diagonal braces extending from said racks to said cover, and springs designed to hold the cover

in an elevated position, as and for the purpose specified.

In witness whereof I have hereunto set my hand in the presence of two witnesses.

ENGWALD JHON SORTLAND.
